UNITED STATES PATENT OFFICE.

J FRANK ALLARD, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed May 13, 1921. Serial No. 469,114.

To all whom it may concern:

Be it known that I, J FRANK ALLARD, a citizen of the United States, residing in Brooklyn Borough, in the county of Kings, 5 city and State of New York, have invented certain new and useful Improvements in Typewriting Machines, of which the following is a specification.

This invention relates to sound-deadening 10 hoods or casings for typewriting machines, and is in the nature of improvements on such casings as shown in the application of John Waldheim, No. 466,820, filed May 4, 1921.

15 In casings of this kind, in order to have the same as light as possible, it has been proposed to make them of thin sheet-metal reinforced with skeleton framework.

The hinged cover of the casing is greatly 20 lengthened, so as to be sufficiently roomy to accommodate the traveling carriage of the typewriter. Nevertheless this expansive cover must be light, because it has to be raised quickly and lowered quickly at frequent intervals, and must not tire the operator, nor can it be self-destructive because 25 of its momentum, when arrested in its upward and downward movements. The cover therefore must be in the nature of thin sheets 30 of metal. Notwithstanding such weakness, it must be stiff, as otherwise it could not fit accurately and reliably to the top of the body of the casing, over the greatly extended lines of contact. This condition is difficult to meet, because a large weak structure 35 tends to get into a skewed or warped condition, thereby preventing full closing of the cover down upon the body, and leaving cracks through which sound may escape, defeating the advantage of a sound-muffling 40 casing. Both the roomy cover and the roomy body of the weak casing are subject to the same trouble of becoming warped in various ways, whereby close fitting of one 45 to the other is not secured, and hence the cover cannot be completely closed. This trouble is particularly present in former casings, where the walls, being made separately and then joined together, have lines 50 of weakness at the corners or joints, which increases the susceptibility of the body and cover to the skewing or warping trouble mentioned.

These and other troubles are overcome by

providing both a body and a cover having 55 thin walls, yet with great stiffness at the corners in place of great weakness, and without liability of skewing or warping of either the body or the cover, and with assurance that the cover and body will always close tightly along all lines. The cover, moreover, is of the requisite lightness, notwithstanding its cumbersome size and form.

The cover consists of a single die-casting 65 of relatively light structural metal, the walls being substantially thinner and much lighter than would be practicable with brass or other ordinary castings, and the corners contributing elements of rigidity and stiffness, 70 inasmuch as the end or side walls of the casting constitute flanges integral with the front, rear and top walls, forming a structure of great stiffness, although light, and notwithstanding its enormous proportions. 75

The body is also required to be of light construction, notwithstanding its great size, and not to be susceptible to bending and warping, for reasons above given in connection with the cover; and to this end the 80 body is devised of a back and side walls forming a single die-casting of light structural material, whereby the walls may be made thinner than would be practicable with brass or other ordinary castings, while 85 the side walls serve as flanges for the back wall, producing a boxing which is open at its front for the introduction of the typewriter keyboard therethrough; a vertical cross-plate connecting said side walls above 90 the keyboard, and contributing to the rigidity of the structure; said plate being preferably detachable and bolted to the side walls.

The side walls are placed relatively close 95 to the side of the typewriter, and have overhanging or outwardly-extending portions co-extensive with the cover and co-operating therewith to form chambers to accommodate the travel of the confined carriage, these 100 overhanging portions preferably having upstanding integral flanges at their ends contributing greatly to stiffness and dependability of the rambling body structure.

In the casing herein illustrated, there is 105 provided a detachable front plate to facilitate placement of the typewriting machine within the casing, the front plate being pro-

vided with lugs having holes to align with holes in co-operative lugs on the casing, so that bolts may be inserted into said openings to secure the plate in place.

5 Other features and advantages will hereinafter appear.

In the accompanying drawings,

Figure 1 is a sectional side view of the casing as seen from the right-hand end, and 10 shows the cover plate detached from the base.

Figure 2 is a combined front elevation and section of the casing.

Figure 3 is a top plan view of the casing 15 without the cover, and showing the front plate detached.

The various parts comprising the casing are cast of any well-known material suitable for die-casting purposes. The casing comprises a base or box-like body portion 10, to which is pivoted a cover 11 by means of a hinge 12, the forward edge 13 of the cover forming, with the upper edge 14 of the front wall of the body portion, a slot 15 through 20 which various handles, including the line-space handle 16, the carriage-return handle 17 and the carriage release handle (not shown) may project, so that the platen 18 of a typewriting machine 20 within the casing may be line-spaced and the carriage 21 thereof returned to the beginning of a new line without lifting the cover 11.

The body portion 10 comprises two angular side walls 22, a front wall 23, and a rear 35 wall 24. The rear wall has at its upper edge a re-enforcing rib 25 from which extend rounded projections or knuckles 26 forming the lower part of the hinge 12. The rear wall 24 is also provided at its 40 lower edge with a re-enforced rib 27, from which extend vertically upward two re-enforcing ribs 28 to strengthen the wall 24, said wall being further provided with two short ribs 30 near the ends thereof.

45 Each end wall is provided with a lower base rib 31, which is a continuation of the rib 27 extending along the bottom of the rear wall. Two ribs 32 extend first upwardly from the rib 31 along the vertical part 29 of the side wall 22, then over the horizontal portion 33 of said wall, and then again vertically along a second vertical portion 34 of said wall (Figure 2). The ribs 32 terminate in upper ribs 35 extending 50 along the upper edges of said walls and forming ledges to support the cover when the casing is closed.

The front wall 23 of the body portion 55 may be provided with an opening 36 to facilitate the insertion of the machine 20 into the casing, thus forming two end portions 37, the latter being re-enforced by horizontal ribs 38, which form continuations of the upper ribs 35 of the side walls and 60 extend vertically downward along the inner

edges of the end portions 37. A detachable cover plate 40, hereinafter described, is provided to close the opening 36 in the front wall after the machine has been placed within the casing.

70 The cover is dome-shaped and provided with a rear wall 41 having at its lower end a rib 42 from which extend knuckles 43 to form the upper part of the hinge 12, the knuckles 26 and 43 being alternately arranged as in Figure 2, and perforated to receive the pin 44 of the hinge. The cover is further provided with two side walls 45, which are joined by the rear wall 41, the latter curving upwardly and forwardly and so terminating at 46, and a cross-bar 47 at the front. An opening 48 is formed between the forward termination 46 of the rear wall and the cross-bar 47, so that a work-sheet around the platen 18 may be observed. To 85 close the opening 48, there is provided a glass plate 50 supported at its forward end within a groove 51 in the front bar 47 and at its rear end by clamps 52 secured to a rib 53 formed at the end 46 of the continuation of the rear wall, the clamps being held in place by screws 54. The side walls of the cover are reinforced by three ribs 55 which extend vertically downward along 90 said walls and terminate in horizontal ribs 56, said horizontal ribs engaging the ledges 35 of the body portion 10. Strips of felt 59 are provided on said ledges 35 to facilitate a noiseless closing of the cover.

To keep the slot 15 closed, through which 100 the handles 16 and 17 project, so as to prevent emission of sound from the casing while the typewriter is being operated, there is provided a slot-closing cushion 57 secured to the lower edge 13 of the front bar 47 of 105 the cover, said cushion being oppositely disposed to a co-operative cushion 58 secured to the upper edge of the removable plate 40, the handles 16 and 17 being readily movable between said cushions.

110 To assist in locating the machine within the casing, there may be provided abutments 60 cast on the rear wall 24 and extending forwardly therefrom, each abutment being provided with a cushion 61 of 115 sound-deadening material to engage the rear corners or posts 62 of the machine. After the machine has thus been located, the front plate 40 may be against the front wall to close the opening therein. To assist in 120 locating and fastening the front plate 40, it may be provided with lugs 63 to be inserted between co-operative lugs 64 on the front wall, the lugs 63 and 64 having holes 65 and 66, respectively, into which, after they are 125 brought into alignment, there may be inserted bolts 67 one at each side of the casing, the bolts 67 being provided with finger-pieces 68 to facilitate their manipulation. The front plate is provided with abutments 130

70 having cushions 71 of sound-deadening material to engage the front corner posts 72 (Figure 3) of the machine, said abutments being oppositely disposed to the abutments 5 60 on the rear wall, and all of the abutments serving to clamp the typewriting machine within the casing. The front plate has a cutout 73 so that it may straddle the usual keyboard section 74 of the machine.

10 A finger-piece 69 is cast on the front bar 47 by which the cover 11 may be manipulated.

It will be understood that the casing may be lined with felt 75 or any other suitable sound-deadening material. The felt at the rear may be provided with grooves into which the ribs fit, thus providing an unbroken surface on the interior of the casing to prevent the work-sheet from being caught 20 while traveling back and forth with the carriage.

Variations may be resorted to within the scope of the invention, and portions of the improvements may be used without others.

25 Having thus described my invention, I claim:

1. In a casing for a typewriting machine, the combination of a cast body portion comprising side walls, re-enforcing ribs cast on 30 the side walls, a cast cover comprising side walls, re-enforcing ribs cast on the side walls of said cover, cast ribs extending along the top edges of the side walls of the body portion to form ledges, and cast ribs extending along the lower edges of the side walls of 35 said cover to rest upon said ledges.

2. In a casing for a typewriting machine, the combination of a cast body portion comprising side walls, re-enforcing ribs cast on the side walls, a cast cover comprising side walls, re-enforcing ribs cast on the side walls of said cover, cast ribs extending along the top edges of the side walls of the body portion to form ledges, cast ribs extending along the lower edges of the side walls of 40 said cover to rest upon said ledges, a re-enforcing rib cast on the upper edge of said body portion, a re-enforcing rib cast on the lower edge of the cover, perforated projections on said two last-named ribs, and a rod extending through the perforated projections to form a hinge for said cover.

3. In a casing for a typewriting machine, the combination of a body portion having 45 a base, a rib cast at the bottom thereof, four walls rising from said rib, each of said walls having re-enforcing ribs cast thereon, and a cover pivoted on the rear wall of the body portion.

60 4. In a casing for a typewriting machine, the combination of a body portion having a base, a rib cast at the bottom thereof, four walls rising from said rib, each of said walls having re-enforcing ribs cast thereon, 65 one of said walls having an opening, a

cover-plate to close said opening, lugs cast on the open wall at the edges of the opening, co-operative lugs cast on the cover-plate, means associated with said lugs to fasten said cover-plate to said casing, and a cover 70 pivoted on said body portion.

5. In a casing for a typewriting machine, the combination of a cast body portion comprising four walls, one of said walls having an opening therein to permit the machine to 75 be introduced into said casing, abutments cast on the wall opposite to the wall having the opening therein, said abutments being adapted to engage the frame of the typewriting machine to assist in locating said machine relative to the casing, a cover-plate to close the open wall, means to secure said cover-plate in its closed position on said casing, and abutments cast on said cover-plate to engage the frame of the machine. 85

6. A sound-deadening casing for a typewriting machine comprising a keyboard, having upper overhanging side portions to accommodate the travel of the typewriter-carriage, said casing comprising a body-portion and a lid, said body-portion having side and rear walls and a front wall having an opening through which the keyboard projects, all forming part of a single die-casting, the side walls having laterally-extending portions to form the floors or bottoms of said overhanging side portions of the casing, said body-portion having projections or means to be engaged by feet of the typewriter, to locate the machine in the 100 casing with the keyboard projecting through said opening, said projections integral with said casting.

7. A sound-deadening casing for a typewriting machine comprising a keyboard, having upper overhanging side portions to accommodate the travel of the typewriter-carriage, said casing comprising a lid, a body-portion having side and rear walls and a front wall through which the keyboard projects, all consisting of a single die-casting, the side walls having laterally-extending portions to form the floors or bottoms of said overhanging side portions of the casing, and a member to close the front 110 wall around the keyboard, said casing having on the rear wall of the body-portion and on said closing member opposed projections or means for engagement with the four feet of the typewriter to locate the machine in the casing. 115

8. A sound-deadening casing for a typewriting machine, having upper overhanging side portions to accommodate the travel of the typewriter-carriage, said casing comprising a body-portion and a lid, the lid hinged to the body-portion and comprising front, rear and side walls, and a top having its forward portion inclined downwardly towards the front, all formed of a 125 130

single die-casting, said lid having a sight-opening near the front thereof and being cast with a groove at the forward edge of said opening, said sight-opening being closed by a transparent plate having its lower edge inserted in said groove and being otherwise secured to said lid, the hinge-members on said body-portion and lid being so shaped as to form a close joint between the rear walls of the body-portion and lid, and to provide a substantially smooth outer surface over the hinges when the lid is closed.

9. A sound-deadening casing for a typewriting machine, said casing being composed of moldable material and comprising a molded body-portion with an open front, a molded lid to fit on said body-portion, and a molded cover-plate for said open front.

10. A sound-deadening casing for a typewriting machine, having upper overhanging side portions to accommodate the travel of the typewriter-carriage, said casing comprising a body-portion and a lid, said body-portion having front, side and rear walls formed of a single die-casting, the rear wall extending above said side walls and being provided with reinforcing ribs running to the top thereof and with perforated projections forming hinge-members, said lid having front, rear and side walls and a top, the rear wall of the lid being provided with perforated hinge-members to co-operate with the hinge-members of the body-portion and the side walls of said lid extending below the lower edge of the rear wall, so as to engage the side walls of the body-portion throughout their length when the cover is closed.

11. The combination of a typewriting machine having a carriage and a sound-muffling casing enclosing the machine and fitted thereto, said casing comprising a body having hinged in rear thereto a cover extended to accommodate the travel of the carriage and provided in its top with a window, said body having a rear wall and side walls fitting to the bottom of said cover, said cover having a top, a rear wall and sides forming thin sheets of light structural metal stiffened by corners formed by die-casting the cover to form one rigid piece, the side walls constituting integral stiffening flanges for the lengthened top and rear walls.

12. The combination of a typewriting machine having a carriage and a sound-muffling casing enclosing the machine and fitted thereto, said casing comprising a body having hinged in rear thereto a cover extended to accommodate the travel of the carriage and provided in its top with a window, said body having a rear wall and side walls fitting to the bottom of said cover, said cover having a top, a rear wall and sides forming thin sheets of light structural metal stiffened

by corners formed by die-casting the cover to form one rigid piece, the side walls constituting integral stiffening flanges for the lengthened top and rear walls, and the side walls being also provided with integral bottom stiffening flanges.

13. The combination of a typewriting machine having a carriage and a sound-muffling casing enclosing the machine and fitted thereto, said casing comprising a body having hinged in rear thereto a cover extended to accommodate the travel of the carriage and provided in its top with a window, said body having a rear wall and side walls fitting to the bottom of said cover, said cover having a top, a rear wall and sides forming thin sheets of light structural metal stiffened by corners formed by die-casting the cover to form one rigid piece, the side walls constituting integral stiffening flanges for the lengthened top and rear walls, said body structure formed of a single die-casting of light structural metal and open at its front for the projection of the typewriter keyboard therethrough, a vertical plate connecting the side walls of said body and co-operating therewith to produce a rigid structure, and means detachably fastening said plate to the side walls.

14. The combination of a typewriting machine having a carriage and a sound-muffling casing enclosing the machine and fitted thereto, said casing comprising a body having hinged in rear thereto a cover extended to accommodate the travel of the carriage and provided in its top with a window, said body having a rear wall and side walls fitting to the bottom of said cover, said cover having a top, a rear wall and sides forming thin sheets of light structural metal stiffened by corners formed by die-casting the cover to form one rigid piece, the side walls constituting integral stiffening flanges for the lengthened top and rear walls, and the side walls of said body placed relatively close to the sides of the typewriting machine and having lateral overhangs or outwardly-extending portions underlying the ends of said extended cover and co-operating with said cover to form chambers to accommodate the travel of the typewriter carriage.

15. The combination of a typewriting machine having a carriage and a sound-muffling casing enclosing the machine and fitted thereto, said casing comprising a body having hinged in rear thereto a cover extended to accommodate the travel of the carriage and provided in its top with a window, said body having a rear wall and side walls fitting to the bottom of said cover, said cover having a top, a rear wall and sides forming thin sheets of light structural metal stiffened by corners formed by die-casting the cover to form one rigid piece, the side walls constituting integral stiffening flanges for the

lengthened top and rear walls, and the side walls of said body placed relatively close to the sides of the typewriting machine, and having lateral overhangs or outwardly-extending portions underlying the ends of said extended cover and co-operating with said cover to form chambers to accommodate the

travel of the typewriter carriage, said overhangs or portions having upstanding integral flanges at their outer ends.
